INVENTOR.

GEORGE S. BRUSH,

BY

John Maurice
ATTORNEY.

UNITED STATES PATENT OFFICE.

GEORGE SEIGFRIED BRUSH, OF ZANESVILLE, OHIO.

DESIGN FOR A CLOCK CASING.

Application filed January 5, 1927. Serial No. 20,284. Term of patent 3½ years.

To all whom it may concern:

Be it known that I, GEORGE SEIGFRIED BRUSH, a citizen of the United States, residing at Zanesville, in the county of Muskingum and State of Ohio, have invented a new, original, and ornamental Design for a Clock Casing, of which the following is a specification, reference being had to the ac-

companying drawing forming part thereof.

In the drawings:

Fig. 1 is a front elevation of the design.

Fig. 2 is an end elevation of the same.

I claim:

The ornamental design for a clock casing as shown.

GEORGE SEIGFRIED BRUSH. [L. S.]
